UNITED STATES PATENT OFFICE.

JOSEPH D. HOBBS, OF MEDIAPOLIS, IOWA.

MEANS FOR PUMPING WATER UNDER HYDRAULIC POWER.

SPECIFICATION forming part of Letters Patent No. 711,858, dated October 21, 1902.

Application filed January 23, 1902. Serial No. 90,964. (No model.)

To all whom it may concern:

Be it known that I, JOSEPH D. HOBBS, a citizen of the United States, residing at Medi-
5 apolis, Des Moines county, Iowa, have in-
vented certain new and useful Improvements
in Means for Pumping Water Under Hyd-
raulic Power, of which the following is a speci-
fication.

My invention relates to means for pumping
10 water under hydraulic power; and it con-
sists in the features and combinations of
parts hereinafter particularly described, and
pointed out in the claims.

In the accompanying drawings, Figure 1 is
15 a side view of the invention with parts in sec-
tion. Fig. 2 is a vertical sectional view of the
invention. Fig. 3 is a plan view of Fig. 2
with parts in section. Fig. 4 is a sectional
20 plan view substantially on line 4-4 of Fig. 2.
Fig. 5 is a perspective view of a detail. Fig.
6 shows a supply for the hydraulic power.

In the drawings the pumping-cylinder 1 is
25 of substantially ordinary form, having heads
2, a pumping-piston 3, suitably packed, and
a hollow piston-rod 4, extending through stuff-
ing-boxes 5, carried by the partitions or heads
30 2. The extreme ends of the piston-rod are
provided with piston-heads 6, working in
chambers 7 and forming continuations of the
casing of the pump-cylinder. These cham-
35 bers have reduced extensions 8, in which the
piston-heads move. Hydraulic power is sup-
plied to the said chambers 7 8 through ports
9 from a valve-casing 10, which contains a
40 sliding valve 11 of cylindrical form. This
valve has ports 12 at its upper and lower
ends arranged to communicate alternately
with the upper and lower chambers 7 and 8
through the upper and lower ports 9. The
45 valve has sliding movement in its casing, be-
ing held and guided by a pin-and-slot con-
nection 13 14. The valve has fixed to its in-
terior two heads 15, with an air-chamber
50 16 is connected with these heads and extends
beyond the casing, having hollow bodies or
floats 17 on its outer end. Pressure-water
is supplied to the valve-casing and to the
55 ports 12 and 9 from a pressure-chamber 18,
which connects at proper times with the in-

terior of the valve through the ports 19 and
20, formed, respectively, in valve-casing and
in the cylindrical wall of the valve. From
Fig. 4 it will be seen that the pump-cylinder 55
is arranged eccentric or to one side of the
center of the main casing 21, and this will
leave a chamber 18 between the two, which I
utilize as the pressure-chamber, to which the
pressure-water is supplied. In this pressure- 60
chamber, as before stated, the valve-casing
is arranged as shown in Fig. 4. The pres-
sure-water is supplied from any suitable
source through inlet-pipes 22, branching off
from a main supply-pipe 23. These branch 65
pipes extend through upper heads 23' 24',
with which the main casing is provided at the
upper end thereof.

The water to be pumped from the well in
which the apparatus is placed is supplied to 70
the pump-cylinder through ports 24, formed
on the outer or main casing one above and
the other below the position of the pump-
piston. These ports are controlled by inlet
75 check-valves 25, working in small cylinders
26, through which the ports 24 are formed.
These valves besides controlling the flow of
water from the well into the pump-cylinder
control also the outlet of the water from the
80 pump-cylinder to the discharge-pipes 27, con-
nected one to the upper small cylinder 26 and
the other to the lower cylinder 26, this latter
connection being made through the pipe 28.
Referring to Fig. 4, the valve 25 is in its po-
sition to allow the water from the well to flow 85
into the pump-cylinder through the port 29,
forming a continuation of the port 24. This
inflow of water to the pump occurs, of course,
whenever the pump-piston moves away from
the valve toward the opposite end of the cylin- 90
der, the valve then acting as an ordinary inlet-
valve. When the pump-piston moves toward
either end of the pump-cylinder, the valve at
that end closes upon its seat at 30, thus clos-
ing communication with the well and opening 95
communication through the port 31 with dis-
charge-pipe 27, before mentioned. The main
casing is closed also at its lower end by a head
32, thus completing the pressure-chamber 18
at the lower end of the apparatus. The valve 100
is controlled by the movement of the pump-
piston, and for this purpose I provide

latches or levers 34, one arm 35 of which is in the path of the piston-head, and the other arm carries a valve-disk 36 to close a discharge-port 37, leading from the end pressure-chamber, and this arm also carries a catch-pin 38, arranged to engage the float 17 at that end of the valve.

It will be understood that the apparatus is submerged in the water which is to be lifted, and supposing the parts to be in the position shown in Figs. 1 and 2 and suitable connection is made with the supply of hydraulic power the operation will be as follows: The pressure-water entering through the pipes 22 into the pressure-chamber enters the upper part of the valve-casing and passes into the upper portion of the valve through the ports 19 and 20, and thence passes by way of the ports 12 and 9 into the upper piston-chamber 8 and acting here upon the larger upper side of this piston the same, together with the pump-piston, will be forced down and the water contained in the pump-cylinder below the pump-piston will be forced out through the port 24 and will pass thence through the pipe 28 to the discharge-pipe 27. As the pump-piston moves down the water from the well flows through the ports 24 and 29 past the valve 25 into the pump-cylinder on the upper side of the pump-piston ready for its delivery through said port 29, port 31, and discharge-pipe 27 when the pump-piston makes its upward stroke. As the pump-piston is about to complete its downward movement the upper pressure-piston strikes the arm 35 of the catch and swings it inwardly, and this action effects two purposes. It withdraws the catch-pin from the float and allows the valve to immediately reverse its position under the pressure of the water in the upper part of the valve acting upon the fixed head 15 in the valve, it being understood that at this time the lower portion of the valve is free from pressure by reason of the fact that the inlet-opening 20 of the valve is out of line with the inlet-opening 19 of the valve-casing. The reversal of the valve cuts off the water from the upper pressure-chamber and admits the pressure-water to the lower pressure-chamber, and the pumping-piston is thus moved upwardly by the hydraulic power acting upon the lower pressure-piston 6. The operation of the catch-lever 34 in the upper pressure-chamber causes the valve-disk 36 to be removed from the discharge-opening of the upper pressure-chamber 8, so that the water is free to discharge from this upper end as the upper pressure-piston moves upwardly. The same action takes place at the lower pressure-chamber when the pumping-piston moves downwardly. A suitable spring 35^x may be employed to press the catch-levers outwardly when pressed inwardly. The catch-lever is held by contact of its pin with the side of the float. By employing floats in connection with the valve the action of this valve is rendered

easy, as the float tends to sustain the weight of the valves.

It will be noticed from Fig. 2 that the piston-rod is hollow and the pressure-pistons 70 form closures for the upper ends thereof, thus providing a float for the pumping-piston.

The tank for supplying the hydraulic power is shown in Fig. 6, the discharge from this tank consisting of a downwardly-extending 75 tube, which, as shown, is tapered. This is connected with the supply-pipes leading to the pressure-chamber. A suitable weight may be employed, as shown in Fig. 6, to get the desired pressure of water. This weight 80 is supported by a float X, which fits the tank closely at its lower edge. The float is filled with air, and any suitable number of weights may be arranged thereon to press it down. From the float a stem y extends upwardly. 85 This is in the form of a tube perforated to supply air within the tank above the said float.

I claim as my invention—

1. In combination, a pumping-cylinder, a 90 pumping-piston therein having its piston-rod extending through the head of the cylinder, pressure-pistons on the ends of said piston-rod, pressure-chambers in which said pressure-pistons operate, a valve controlling the 95 inlet-ports to the pressure-chambers, said valve being of elongated form, a head fixed within the valve, means for holding the valve in the position into which it is set, said means being adapted to be controlled at the final 100 movement of the said pressure-piston, substantially as described.

2. In combination, a pumping-cylinder, a 105 pumping-piston therein, a piston-rod extending through the heads of the pumping-cylinder, pressure-chambers at the ends, pressure-pistons connected with the piston-rods in said chambers, a valve for controlling the hydraulic supply to the pressure-chambers, said valve having a piston to be acted on by the 110 pressure-water, means for holding the valve in the position to which it is moved, valves for controlling the outlet of the water from the pressure-chambers, said valves and holding means being controlled by the movement 115 of the pressure-piston, substantially as described.

3. In combination, a main casing, a pump-cylinder arranged eccentric thereto leaving a space between one side and the inner wall 120 of the casing to form a pressure-chamber, a valve-casing arranged in said space and having ports communicating therewith, a valve operating in said casing, a pumping-piston in the pumping-cylinder, means for supplying 125 the pressure-chamber with water, and pressure-chambers having pistons therein connected with the pumping-piston, the supply to said pressure-chambers being controlled by the valve, substantially as described.

4. In combination, a casing, a pumping-cylinder arranged therein eccentric to the

casing to form a pressure-chamber between the pumping-cylinder and said casing, means for supplying water to said pressure-chamber, a valve controlling the flow of water thereto, 5 pressure-pistons operated by the pressure of water, discharge-pipes and valves 25 controlling the outlet of the water through said pipes from the pumping-cylinder and the inlet to

the pumping-cylinder, substantially as described.

In testimony whereof I affix my signature in presence of two witnesses.

JOSEPH D. HOBBS.
